UNITED STATES PATENT OFFICE

JOHN B. HAWLEY, JR., OF MINNEAPOLIS, MINNESOTA

STEAM-BOILER STRUCTURE

Application filed April 24, 1928. Serial No. 272,556.

This invention relates to steam boilers and especially to the generation of steam in an installation in which the boiler is subjected to direct action of the fire.

5 The object of the invention is the provision of a boiler installation including a fire box and a boiler located thereabove, and in which the boiler is provided with a plurality of radially extending copper fins exposed directly to the heat rising from the fire box, said fins being metallically connected to the boiler, as by a welding process, whereby to permit the lower edge portions of said fins to be contacted directly by the heat of the 10 fire box and to conduct said heat, absorbed as radiant energy, to the upper portions of the fins and thence to the boiler shell and to the water therein.

Another object of the invention is the 20 provision of a member which surrounds the outer vertically-extending edges of the copper fins, thereby providing, between each adjacent pair of fins, a vertical channel for the passage of the heated air currents rising from the fire box, whereby to permit the body portion of the fins to absorb a large portion of the heat passing through the said channels and to transfer said heat directly to the boiler shell.

25 A still further object of the invention is the provision of an installation wherein the boiler shell is so mounted above the fire box that the bottom portion of the shell is positioned below the lower edges of the copper 35 fins and surrounded by firebrick, thereby insuring that the more intense heat may contact the bottom and lower sides of the shell before reaching the copper fins.

Other objects of the invention will be 40 made apparent in the following specifications, when read in connection with the drawing forming a part thereof.

In said drawing:

45 The figure is a partly sectional, fragmentary, side elevation, of an installation embodying my invention.

Now referring specifically to the drawing, 50 1 indicates a steel shell which surrounds a fire box 2, preferably of cylindrical formation, as here illustrated. The inner face of

the shell 1 is lined with the usual fire brick 3, the grates 4 resting below a furnace door, (not here shown) and an ash door 5 being positioned below the grate.

55 The boiler 6 is composed of drawn steel, and a plurality of copper fins 7 are secured thereto by a welding process, preferably as described in my co-pending application Ser. No. 222,541, filed Sept. 28, 1927, whereby to provide a permanent metallic connection between the fins and the steel boiler body. It is to be noted that each of the fins 7 has its inner vertical edge in welded contact with the body of the boiler 6, the vertical length of each fin being approximately one-half the length of the boiler, the latter therefore 60 extending above and below the zone of the fins, the fins being in substantial parallelism and radiating from the central boiler axis.

65 The steel tank or boiler 6 is provided with a seamless bottom, and with a head 8 welded into the top. A water inlet pipe 9 and a steam outlet pipe 10 extend through the stack 11 and enter the top of the boiler, the water inlet extending downwardly within the latter to a point substantially below the bottom edges of the fins 7. A hand-hole 12, for cleaning purposes, is provided in the top of the tank.

70 A cylindrical steel shell 13 is positioned with its lower rim upon the top of the fire bricks 3, the upper end of said shell being secured to the lower periphery of the stack 11. The lower ends of the fins 7 also rest upon the said fire bricks 3, and serve to support the boiler in proper position centrally of the shell 13. Located adjacent and in contact with the extreme outer edges of the copper fins 7, is a cylinder 14 composed of high-temperature metal, such as stainless steel, a cylinder of asbestos, or other insulating material 16, being positioned between the cylinder 14 and the shell 13. The customary water gage devices 15 are also connected to the boiler 6.

75 90 In the structure as disclosed, it will be noted that the steel cylinder 14 contacts the outer edges of all of the fins 7, and constitutes with said fins, and the wall of the boiler 6, a multiplicity of vertically extending chan-

nels permitting the passage therethrough of the products of combustion in the fire box.

With the elements arranged as described the highly heated products of combustion rising from the grate first contact the lower end of the boiler 6, and are deflected against the fire bricks 3, permitting the latter to absorb some of the radiant energy of the heat, and thereby lower the intensity of action on the copper fins 7. As the heated products of combustion reach the fins 7, they pass upwardly through the channels provided therebetween, certain portions of the gases contacting the wall of the boiler 6, and other portions operating to raise to and maintain the copper fins at a high temperature, which temperature is conducted by the fins to the body of the boiler 6, and thence to the water therein contained.

Surrounding and in contact with the outer edges of the fins 7, is a cylinder 14 formed of high temperature steel, the purpose of said cylinder being to close the space between adjacent fins thereby preventing lateral egress of the hot gases passing upwardly through the flues formed therebetween. The asbestos covering 16 surrounds the cylinder 14, insulating against radiation to the outside air.

The water level in the boiler 6 is maintained at a point above the tops of the copper fins 7, so that the heat conducted by the fins to the boiler shell 6, will be transmitted directly to the water contained therein rather than to steam, as would be the case were the water level allowed to drop to a point below the level of the fins. Steam is a very poor conductor of heat, the contrary being true of water in circulation. It is important that the fins and the shell 6 be allowed to rapidly give up the heat absorbed from the fire box, and the logical cooling medium is the cold water entering the shell from the inlet pipe 9. If the shell were kept largely full of steam, at steam temperature, it is obvious that the heat transfer from the fins and shell, to the water, would be relatively slow.

The relative dimensions of the copper fins 7 are important, in that they must be of a cross-section and length sufficient to absorb the necessary heat from the fire box, and from the gases passing through the flues, and directly to the boiler shell and thence to the relatively cool water therein contained. In the drawing I have illustrated the fins 7 in the form of copper slabs of substantially the same thickness as the wall of the shell 6, the length of the fins being slightly greater than the diameter of the boiler, and the width of the fins being approximately one-third of the diameter of the boiler 6. In this structure, by properly regulating the heat in the fire box and maintaining a proper water level, the lower end of the boiler 6 will receive the more intense heat, and transfer it to the water contained therein, in the usual man-

ner. But a heat of similar intensity will also be applied to the lower ends of the copper fins 7, and, because of its large cross sectional area, each fin will quickly conduct the heat to the point of weld with the shell, and thence directly to the water therein contained, simultaneously and progressively conducting the heat from the lower portion of the fin to the upper portions thereof, and thence through the welded joint to the water, as will be understood. During this operation the highly heated gases are passing through the flues in close contact with the sides of the fins, and are constantly adding heat increments to be subsequently conducted laterally through the fins to the water within the boiler. If the copper fins 7 were not properly dimensioned, with respect to the thickness of the shell 6, and with regard to the heat of the fire box, the fins would become burned and rendered useless, and this would also be true if the water in the shell were allowed to fall substantially below the level of the top of the fins.

Demonstrations of a boiler so equipped, extending over a period of one year, have proven that water may be converted into steam in 3 minutes, as against 60 minutes necessary to form steam in a similarly dimensioned boiler, unequipped with such copper fins, and under the same heating conditions.

Modifications of the structure herein disclosed will be suggested to those skilled in the art, but my invention covers all embodiments falling fairly within the scope of the appended claims.

I claim:

1. A steam generator including a firebox, a boiler positioned within said firebox, and a plurality of fins of relatively high conductivity metallically connected to said boiler and supporting said boiler in operative position.

2. A steam generator including a firebox having a heat resisting lining, a boiler positioned in said firebox, and a plurality of fins of relatively high conductivity metallically connected to said boiler and seated on said lining to support said boiler in operative position.

3. A steam generator including a firebox, a boiler positioned vertically within the firebox, a plurality of fins of relatively high conductivity metallically connected to said boiler, and means in said firebox adapted for contact by said fins to support said boiler in position.

4. A steam generator including a firebox, a boiler positioned vertically therein, a plurality of copper fins metallically secured to and radiating from said boiler, and means in said firebox adapted for contact by said fins to support said boiler in position.

In testimony wheroef I affix my signature.
JOHN B. HAWLEY, JR.
